SPOOL OR REEL

Filed May 14, 1928

Inventor
Everett H. Kneen
Symon, Ladd & Nichols
Attn:

UNITED STATES PATENT OFFICE

EVERETT H. KNEEN, OF ANSONIA, CONNECTICUT

SPOOL OR REEL

Application filed May 14, 1928. Serial No. 277,473.

This invention relates to improvement in spools or reels particularly adapted for adhesive tape. Strips of adhesive tape are wound upon a plurality of tubular cores mounted upon a suitable mandrel, then the cores, with the coils of tape, are separated and ends are applied to the core, and the object of this invention is a simple construction which provides a core of sufficient rigidity and to which the end-pieces may be readily and firmly attached, and the invention consists in the construction as hereinafter described and particularly recited in the claims.

In the accompanying drawings:

- 15 Fig. 1 is a front view of a reel or spool constructed in accordance with my invention;
- Fig. 2 is an end view of the same;
- Fig. 3 is a sectional view on the line 3—3 of Fig. 1 enlarged;
- 20 Fig. 4 is a sectional view on the line 4—4 of Fig. 1;
- Fig. 5 is a side view of the core detached;
- Fig. 6 is an end view thereof;
- Fig. 7 is a side view of an eyelet detached;
- 25 Fig. 8 is an inside view of the same;
- Fig. 9 is a sectional view illustrating a modified form of my invention;
- Fig. 10 is a sectional view showing another modified form of my invention;
- 30 Fig. 11 is an edge view of the same; and
- Fig. 12 is an inside view of the same.

In carrying out my invention, I employ a core 15 formed from a strip of sheet-metal and rolled to form a tube, the ends 16 being turned in to form shoulders 17. To connect the edges of the core, I form one end of the strip with parallel slots 18 and raise the metal between the slots to form bridges 19. The other end of the strip is formed with tongues 20 which pass through the slots 18, below the bridges 19, and pressure is then applied to clamp the tongues by the bridges. In this way the tongues are bent transversely so as to be firmly interlocked. With the cores thus formed, I employ end-plates 21 perforated for the reception of eyelets 22, the necks 23 of which are struck outward to form fingers 24 arranged to engage with the shoulders 17, so as to be firmly interlocked with the core.

50 It is obvious that instead of forming the

eyelets independently of the end-plates 21, they may be formed integral therewith, as shown in Fig. 9 of the drawings, in which the plate 21 is formed with a centrally-arranged inwardly-extending neck 28 provided with fingers 29 to engage with the shoulders 17, or, instead of forming a neck, the plate 27 may be formed with a series of inwardly-projecting fingers 30 provided with projections 31 to engage with the shoulders 17. With this construction I provide a tube or core sufficiently rigid for the purpose and provided with shoulders with which the end-pieces are firmly interlocked.

I claim:

- 1. A spool, comprising a core formed from a strip of metal rolled to form a tube, the abutting edges interlocked and its ends turned inward forming annular shoulders and end-pieces provided with fingers engaging with the said shoulders, whereby the end-pieces are interlocked with the core.
- 2. A spool, comprising a core formed from a strip of metal rolled to form a tube, one edge of the strip formed with parallel slots forming bridges and the other edge formed with tongues extending beneath said bridges, the ends of the core turned inward, whereby annular shoulders are formed and end-plates provided with fingers engaging with said shoulders.
- 3. A spool, comprising a core formed from a strip of metal rolled to form a tube, one edge of the strip formed with parallel slots forming bridges and the other edge formed with tongues extending beneath said bridges, the ends of the core turned inward, whereby annular shoulders are formed, end-plates applied to the ends of the core and eyelets extending through said plates and formed with fingers engaging with said shoulders.

In testimony whereof, I have signed this specification.

EVERETT H. KNEEN.
